James W. Harris.

UNITED STATES PATENT OFFICE.

JAMES WILSON HARRISS, OF CANTON, OHIO, ASSIGNOR TO ELBEL & CO., OF SAME PLACE.

DESIGN FOR A BUCKLE.

SPECIFICATION forming part of Design No. 21,037, dated September 15, 1891.

Application filed June 3, 1891. Serial No. 394,996. Term of patent 7 years.

To all whom it may concern:

Be it known that I, JAMES WILSON HARRISS, a citizen of the United States, residing at Canton, in the county of Stark and State of Ohio, have invented a new and original Design 5 for a Rein-Buckle, of which the following is a specification.

The invention relates to a new and original design for buckles.

10 The object of the present invention is to provide an ornamental and attractive buckle which will add to the appearance of harness.

The essential feature resides in the particular configuration of the buckle and the 15 relative disposition of the parts thereof.

Figure 1 is a perspective view of a buckle, showing my new design. Fig. 2 is a side view of the same. Fig. 3 is a reverse plan view.

20 Referring to the accompanying drawings, 1 designates a buckle consisting of side bars 2, end bars 3, connecting the side bars, a cross-bar 4, and a tongue 5. The side bars are curved and have convex lower edges and

25 concaved upper edges, and the ends of the side bars are convexly curved on their upper edges, and the end bars which connect the side bars have curved upper faces conforming to the configuration of the ends of the

side bars and are flushed with the same. The 30 cross-bar connects the side bars at points intermediate the ends of the latter, and it is provided with a central semicircular enlargement 6. The buckle presents an ornamental appearance and adds to the attractiveness of the bridle and rein to which it may be applied.

What I claim is—

The design for buckles herein shown and described, the same consisting of the curved 40 side bars having convex lower edges and concave upper edges, the upper edges at the ends of the bars being convexly curved, the end bar having curved upper faces arranged flush with the upper edges of the side bars 45 and conforming to the configuration of the same, the cross-bar arranged between the side bars and having a curved lower face and provided with a semicircular enlargement, and the tongue, as set forth.

50 In testimony that I claim the foregoing as my own I have hereto affixed my signature in presence of two witnesses.

JAMES WILSON HARRISS.
